UNITED STATES PATENT OFFICE.

GEORGE GEOFFREY SALE, OF DUNEDIN, NEW ZEALAND.

CONCENTRATOR FOR GOLD-BEARING MATERIAL.

SPECIFICATION forming part of Letters Patent No. 694,199, dated February 25, 1902.

Application filed August 9, 1900. Serial No. 26,361. (No model.)

To all whom it may concern:

Be it known that I, GEORGE GEOFFREY SALE, mining engineer, a subject of the Queen of Great Britain, residing at 37 Moray Place, in the city of Dunedin, in the British Colony of New Zealand, have invented certain new and useful Improvements in Concentrators for Gold-Bearing Material, of which the following is a sufficiently full and exact description to enable any person skilled in the art or science to which the said invention appertains to make and use the same.

The object of this invention is to provide a concentrator for separating gold, especially from black sand on dredges, where space is an object, with self-acting and self-cleansing moving mattings, which can be altered as to speed of moving without stopping the dredge. These mattings may be placed on ordinary tables; but the tables may be smaller than those with fixed mattings for treatment of any given amount of material and smaller than those which having moving mattings have but imperfect means of cleansing their surfaces. For this purpose a matting of suitable gold-catching surfaced flexible material is stretched between rollers, a portion being deflected into a tub or box containing water by passing under a roller, and it is kept at an even tension by one of the rollers being weighted by balance-weights for this purpose. This matting is slowly revolved upstream or against the flow of the wash on the inclined surface of the tables by specially-constructed gearing, receiving power from the dredge machinery and capable of moving the matting quicker or slower at will. At or near the point where the matting enters the water and, in some cases, when it leaves the water a tapper or beater is arranged to strike the matting sharply to free the surface or interstices from the gold and wash sticking to it and allow same to deposit in the box. Fresh water enters the box from any dredge-pump, the surface being maintained by an overflow. The box is emptied in any convenient way, and the contents may be locked in till wanted.

Referring to the accompanying drawings, Figure 1 is a longitudinal section of the apparatus, and Fig. 2 is a plan of same. Fig. 3 is an enlarged detail of a suitable form of cam to allow of a striking blow being given

to the matting as it revolves. Fig. 4 is a front view of said detail.

A is any box, preferably formed as shown, 55 extended at the top end for receiving droppings as matting turns over end top roller, the other end also extended to receive any water droppings and form an overflow at A³.

A' is a suitable place for the inflow of clean 60 water.

A⁵ is a lid that may be locked for emptying the box.

B B is the endless matting, plush, or such like surface, running around rollers C C at 65 ends and under C', for washing and over C² for tension, which can be adjusted in manner as indicated.

D D is any table placed at the usual angle, and it is obvious that as the matting always 70 presents a clean surface and a fresh face to the wash the tables need not be so large as when the mattings are merely cleaned at intervals.

E is a rod or flapper and is connected to the 75 loose crank E², which is lifted at each revolution by the crank E', which is fixed to the shaft of the conical pulley F². This receives power from G, which is attached to the motive power through the other conical pulley 80 F' and drives the roller C by such as the worm-gearing shown, F. When E' has lifted E² past the upright position, E² being loose on the shaft, falls, this action being accelerated by the spring E³, when B receives a 85 smart blow, such as a carpet receives in being beaten. It will be seen by the motion that this is repeated very frequently. The belt on the conical pulleys control the speed by the usual guide-forks. (Not shown.) 90

I am aware that tables have been invented having movable mattings, some revolving in one direction and some in another; but from the imperfect means adopted to clean the mattings they become clogged and have not 95 been successful in saving gold; but I am not aware that anything approaching my invention is in use.

In this invention any number, size, or suitable materials may be adopted. 100

What I claim, and desire to obtain by Letters Patent of the United States of America, is—

In combination with a concentrator employing an endless belt, of a beater mechan-

ism for the belt, comprising a frame, a horizontal shaft carried by the frame and adapted to rotate said belt, means to transmit power to said shaft, a rigid crank mounted upon said shaft near the end thereof, a loose crank mounted upon the end of the shaft and adapted to be tilted at each revolution of the shaft by said rigid crank, a rod connected to said loose crank, a pivoted flapper connected to

5 to the under side of the frame and also to the

rod, said flapper being adapted to be raised at every revolution of the shaft, and a spring for returning said flapper, rod and loose crank with a sudden jerk to beat the belt, substantially as described.

GEORGE GEOFFREY SALE.
